COLLAPSIBLE TUBE DISPENSING DEVICE
HAVING ROCKABLE TUBE-ENGAGING
MEMBERSCarl F. Nelson, Mill Valley, and Verner A.
Nelson, Oakland, Calif.

Application December 17, 1948, Serial No. 65,758

4 Claims. (Cl. 222—103)

1

Our present invention relates to a collapsible tube supporting and contents extruding device and more particularly to a device that may be attached to the wall of a bathroom for the convenient dispensing of toothpaste or other like commodities, and it has, for its object, the provision of a new and practical arrangement by which the contents of a collapsible tube may be extruded in a simple, clean and convenient manner.

Another object of our invention is to provide an improved collapsible tube supporting device by which the entire contents of a collapsible tube may be discharged in required quantities without a handling of the tube on the part of the user.

Another object of our invention is to provide a new and novel form of gripping and holding means for a collapsible tube contents dispenser.

In the use of toothpaste and shaving creams such as are dispensed in collapsible tubes the tubes generally become distorted and unsightly and often difficult to locate. It is therefore a further object of our invention to provide a combined collapsible tube supporting and extrusion producing means that may be used to support a collapsible tube with its contents in a convenient location where the contents thereof may be dispensed directly upon a brush, or the like, in a simple and convenient manner.

Other objects and advantages of our invention will be in part evident to those skilled in the art and in part pointed out in connection with the accompanying drawing, wherein there is shown by way of illustration and not of limitation a preferred embodiment of the invention.

In the drawing:

Figure 1 is a front view of a device constructed in accordance with a preferred embodiment of our invention.

Figure 2 is a side elevation of the device, as shown in Figure 1 of the drawing, with the tooth brushes indicated by dot and dash lines.

Figure 3 is a bottom view of the device, as shown in Figure 1 of the drawing, with the tooth brushes removed.

Figure 4 is a fragmentary and perspective view of the neck clamping spring means employed in accordance with our invention.

Figures 5 and 6 are fragmentary sectional views showing positions of the parts at various stages of operation, and

Figure 7 is a fragmentary side view partially in section showing a modified form of our device.

While our device may be constructed entirely of metal we have in the accompanying drawing

2

shown an embodiment in which all of the parts can be formed of a plastic material. With this material a very ornamental device can be made up by using plastics of different colors for the different parts of the device. The backing or main supporting bracket, designated by the numeral 10, is shown as having an inverted key hole slot 11 by which it may be hung by a nail or screw upon a wall and at each side there is shown an outwardly extending pin 12 upon which tooth brushes 13 may be suspended for convenient use with the device. Fixed upon and disposed outwardly from and in uniformly spaced relation with the bracket 10 there is a strap-like member 15 that provides a guideway or rail 14 along which a carriage member 15 moves, as will hereinafter appear. This carriage member 15 supports a pair of oppositely disposed rocker-like members 16 and 17 that are respectively mounted upon the carriage 15 by means of transversely extending shafts 18 and 19. At its lower end the bracket 10 is also provided with a horizontally extending shelf-like member 20 that has a triangular aperture 21 through which the neck of a collapsible tube 22 may be extended to dispose the tube 22 in an inverted position. Associated with this shelf-like member 20 there is a double bowed spring 23 which is adapted to engage the neck of the collapsible tube 22 and hold it in cooperating relation with the rocker-like members 16 and 17 of the carriage member 15.

As is more clearly shown in Figures 2 and 3 of the drawing the guide-way 14 is disposed outwardly from the bracket 10 at a distance sufficient to provide a clearance for the base portion of the carriage 15 which is substantially of U-shape with its ends projecting outwardly in parallel relation at opposite sides of the strap-like member which forms the guide-way 14. In these figures of the drawing it will also be noted that the shafts 18 and 19 are projected through outwardly extending parallel portions 24 that form the sides of the carriage 15. The shaft 18 as here shown is located above and outwardly from the shaft 19 so as to provide a space between the rocker-like members 16 and 17 into which the body portion of a collapsible paste dispensing tube may be disposed. As is more clearly shown in Figure 2 of the drawing the rocker-like member 16 has an outwardly extending lever 25 with a thumb pad 26 through which pressure may be applied to rock the rocker-like member 16 about its transversely extending pivotal axis and bring it into pressure exerting relation against the outer surface of the collapsible tube 22. To return the

rocker-like member 16 to its normal inoperative position, the transversely extending shaft 18 upon which the rocker-like member 16 is fixed has a torsion spring 27 that is fixed at its outer end to one side of the carriage member 15 so as to bias this shaft 18 in a clockwise direction. As distinguished from the rocker-like member 16, the rocker-like member 17 is free to turn freely with its supporting shaft 19 so as to permit its intermediate angularly disposed flat surface to turn into cooperation with the corresponding flat surface of the member 16 when pressure is applied to the lever 25. The construction of the rocker-like member 17 is such that an over-balancing weight with respect to the shaft 19 is established. This will cause the member 17 to rotate in a counter-clockwise direction when released. Normally this rocker-like member 17 will assume the position shown in Figure 5 and thus permit the carriage 15 to advance downwardly over the collapsible tube 22 as its contents is extruded therefrom. As a means for limiting the rocking movement of the member 17 there are two inwardly projecting stops 28 and 29 that extend inwardly from the side walls 24 of the carriage 15.

Reference is now made to Figures 3 and 4 of the drawing for a more detailed description of the capturing means which is relied upon to hold the collapsible tube 22 in its vertical position between the cooperating rocker-like members 16 and 17 as above outlined. In these showings it will be noted that the aperture 21 in the shelf-like member 20 is substantially of triangular shape with its apex disposed outwardly and centrally with respect to the bracket 10. This aperture 21 may be made sufficiently large to permit insertion of a tube with its cap thereupon or it may be only large enough to permit the insertion of the neck of the tube with its cap removed. In either event the neck of the tube will project below the shelf 20 a distance sufficient to permit the application of a cap 30 thereto. The double bowed spring 23 is hingedly mounted upon the outer surface of the guide-way 14 by a cleat 31 as indicated in Figure 1, and its bowed ends are brought out from the top of the shelf 20 downwardly through the aperture 21 and crossed within this aperture in such a manner that the extending ends of the spring 23 will engage with the underside of the shelf 20. In this way the crossed ends of the spring 23 will be held in co-operating relation against the neck of the collapsible tube 22. As is more clearly illustrated in Figure 4 the outer ends of the double bowed spring 23, designated by the numeral 32 in Figure 4 of the drawing, are bent out at a right angle so as to provide a finger rest by which they may be compressed to release the neck of an empty tube 22 and permit the insertion of a new tube.

While it is believed that the operation of our improved device will be fully understood in the above, reference is now made to Figures 5 and 6 of the drawing for a more detailed description as to how the rocker-like members 16 and 17 cooperate with each other and engage the walls of a partially flattened tube when in operation. Normally the vertically movable carriage member 15 will drop downwardly until the intermediate surfaces of the rocker-like members 16 and 17 have become engaged with the outwardly flaring sides of the partially flattened collapsible tube 22 and when in this position it will be understood that as pressure is applied to the rocker-like member 16 through an operation of the lever 25, the rock-

er-like member 16 will be turned counter-clockwise about the pivotal axis provided by the shaft 18 and cause its intermediate flat surface to travel inwardly and upwardly against the partially flattened wall of the tube at its point of engagement therewith. At the same time because of the spacing between the rocker-like members 16 and 17, as the rocker-like member 16 rotates counter-clockwise it will transmit a force through the tube 22 to the rocker-like member 17 which will cause this latter member to turn in a clockwise direction about the pivotal axis formed by its supporting shaft 19. As a result of this the two flat intermediate surfaces of the rocker-like members 16 and 17 will be progressively brought into parallel relation with each other at a point where the walls of the tube will be flattened into close contact with each other. This will cause the contents of the tube 22 positioned therebetween to be squeezed toward the neck of the tube. In this operation it will be understood that the two flattened intermediate surfaces of the rocker-like members will first pinch the tube 22 at a point near their upper edges and away from the open end of the tube and as a result there will be no danger of the paste or other commodity carried by the tube being forced back into the bottom of the tube.

In connection with the above described device it should be explained that while the angular disposition of the three tube contacting surfaces of the rocker-like members 16 and 17 is not critical it is important that the opposed intermediate flat surfaces of these rocker-like members be so arranged that when fully compressed they will assume a substantially parallel relationship in a vertical plane.

In Figure 7 of the drawing there is shown a modified form of the invention in which the co-operating rocker-like members are provided with transversely extending flutes which for a portion of their movement are adapted to interact much in the manner of a pair of opposed gears. In this arrangement the vertical movable carriage 15, similar to that above described, is shown as having an outer rocker-like member 33 that is provided with an operating lever 34 which has a thumb pad 35 by which pressure may be applied to operate the device. This rocker-like member 33 has a fluted surface 36 that is eccentric at its upper end and then concentric with respect to a shaft 37 upon which it is mounted and biased by means of a torsion spring in a manner similar to that employed upon the previously described embodiment of the invention. Cooperating with the rocker-like member 33 there is a second rocker-like member 38 which is provided with a fluted surface 39 that is likewise arranged concentric with respect to a supporting shaft 40. With this arrangement it will be seen that as the lever 34 is forced downwardly the fluted surfaces 36 and 39 of the rocker-like members 33 and 38 will tend to become intermeshed and thus progressively squeeze the collapsible tube 22 for a predetermined distance. During this operation the trailing flutes of these two rocker-like members will serve to crimp the walls of the tube as they progress thereover and when the lever 34 is released the carriage 15 will drop down and re-engage the collapsible tube 22 at a new point as determined by these crimps and where the operation may be repeated. In this manner a predetermined quantity of the contents of the collapsible tube 22 may be extruded in a step by step fashion as the lever 34 is operated as above indicated. In other words

the partially collapsible portion of the collapsible tube 22 will be shaped or formed for a more full engagement by the flutes of the rocker-like members 33 and 38 as the carriage 15 moves downwardly with respect thereto.

While we have, for the sake of clearness and in order to disclose the invention so that the same can be readily understood, described and illustrated specific devices and arrangements, we desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described our invention, what we claim and desire to secure by Letters Patent is:

1. In a toothpaste dispensing device of the character described, the combination of a supporting bracket, means carried by said bracket for gripping the neck of a collapsible tube and positioning it in an inverted vertical position, a vertically moveable support mounted upon said bracket for movement along the body of an inverted collapsible tube secured by its neck upon said bracket, a free floating pivotally mounted tube engaging member against which the closed end of a collapsible tube may be disposed, a second pivotally mounted tube engaging member spaced from said first tube engaging member and adapted to engage with the other side of a tube at a point farther removed from said tube neck gripping means, each of said tube engaging members being mounted to pivot about horizontally disposed axes and having cooperating flat angularly disposed surfaces, and a lever means through which pressure may be applied to said second tube engaging member and cause said tube engaging members to pivot about their respective axes, whereby the angularly disposed surfaces of said tube engaging members will be progressively brought into pinching relation with the walls of a tube positioned therebetween.

2. In a toothpaste dispensing device of the character described, the combination of a supporting bracket, means carried by said bracket for engaging the neck of a collapsible tube and positioning it in an inverted position, a vertically movable support mounted upon said bracket for movement along the body of a collapsible tube secured by its neck upon said bracket, a pair of spaced rocker-like members between which the body of the collapsible tube may be disposed, said rocker-like members each being mounted to rock about a horizontally extending axis at opposite sides of the tube when positioned therebetween and having flat angularly extending surfaces disposed at different distances from their axes and adapted to be brought progressively into pinching relation with the walls of a collapsible tube, and a lever extending outwardly from one of said rocker-like members by which pressure may be applied to cause the angularly extending flat surfaces of each of said rocker-like members to be brought progressively into pinching relation

with the walls of a tube positioned therebetween.

3. In a toothpaste dispensing device of the character described, the combination of a supporting bracket, means carried by said bracket for engaging the neck of a collapsible tube and positioning it in an inverted position thereupon, a support slidably mounted upon said bracket for movement along the body of a collapsible tube secured by its neck upon said bracket, a pair of spaced rocker-like members each having a plurality of flat surfaces disposed angularly with respect to each other and between which the body of a collapsible tube may be disposed, one of said rocker-like members being pivotally mounted upon an axis transverse to the axis of said tube and located at one end thereof and the other of said rocker-like members being pivotally mounted upon a transverse axis substantially centrally thereof and below the axis of said other rocker-like member, whereby the angularly disposed surfaces of said rocker-like members will be brought progressively into a pinching relation with the walls of a collapsible tube as said first rocker-like member is turned about its axis, and a lever means extending outwardly from said first rocker-like member through which an operating force may be applied thereto.

4. In a toothpaste dispensing device of the character described, the combination of a supporting bracket, a vertically movable support slidably mounted upon said bracket for movement along the body of the collapsible tube secured by its neck upon said bracket, a pair of spaced rocker-like members each having tube engaging surfaces between which the body of a collapsible tube may be disposed, one of said rocker-like members being pivotally mounted at one end upon an axis transverse to the axis of said tube and the other of said rocker-like members being pivotally mounted substantially centrally thereof upon a transverse axis to one side of and below the axis of said other rocker-like member, whereby said rocker-like members will be brought progressively into pinching relation with the walls of a collapsible tube as first rocker-like member is turned about its axis, a lever means extending outwardly from said first rocker-like member through which a rocking force may be applied thereto, and means carried by said bracket for gripping the neck of a collapsible tube to dispose and hold the body of the tube in cooperating relation with said rocker-like members.
